DOUBLE CYLINDER CIRCULAR KNITTING
MACHINE PROVIDED WITH A NOISELESS
COUPLINGBohumil Charvát, Sezimovo Ústí, Czechoslovakia,
assignor to Svit, národní podnik, Gottwaldov,
CzechoslovakiaApplication March 1, 1949, Serial No. 78,956
In Czechoslovakia March 18, 1948

1. Claim. (Cl. 66—153)

1

The present invention relates to a noiseless coupling for circular knitting machines, more particularly for circular knitting machines having superposed needle cylinders, the coupling being arranged on a counter-shaft rotatable in one direction, or in both directions, in such a way that during the period of normal knitting an efficient connection is provided between the counter-shaft and the main draw-off device, while during the period of to-and-fro knitting the efficient connection is interrupted.

Double cylinder circular knitting machines, and in many cases also single cylinder circular knitting machines, are provided with a discharge drum for the knitted tubular stocking product and heel pockets. The discharge drums are coupled by means of gear wheels with the counter-shaft for relative circular motion, this circular motion being synchronised with that of the knitting cylinders, so that the knitted product is not displaced angularly but moves from the draw-off position under gravity and comes to rest on the bottom of the discharge drum.

However, this positive motion may be applied only to circular knitting, e. g. when knitting tubular or like products.

If stockings with heel pockets are to be manufactured on machines of this type, so that alternatingly a reciprocating movement of the knitting cylinders is required, it is not convenient for the discharge drum with its own weight and that of the knitted product to partake of such movement.

For arresting or interrupting the rotary motion of the product discharge drum in both directions, various arrangements have been designed in the form of couplings which in order to be thrown in and off require a special device operated from the control drum. Amongst the types of couplings hitherto used, the dog clutches, more particularly, produce a noisy shock when the circular movement of the discharge drum with the product in the same is initiated each time a heel pocket has been completed.

A coupling has been designed comprising two rotating members of which one is of cylindrical shape. This cylindrical member, which is provided with a helical groove around its periphery and is keyed on the counter-shaft, co-operates with the other member, i. e. a gear wheel, in which a stud engaging in the helical groove of the cylindrical member is so arranged that during the oscillatory movement of the knitting cylinders the cylindrical member of the coupling receives an oscillatory movement and at the

same time an axial translation. The main disadvantage of a coupling of the type just referred to consists in that one of its members has to perform an axial translation which imposes unfavourable stresses on the coupling stud engaged in the helical groove, on the guide groove itself and on the counter-shaft as well.

Further, a coupling has been designed consisting of two rotating members having their contacting faces provided with grooves of which one extends in radial direction and the other has a spiral configuration, so that in any position the two grooves cross each other. The two grooves serve as a guideway for a sliding block which transmits the movement from one member to the other. The disadvantage of this arrangement resides in the necessity of using a two-part counter-shaft and a sliding block movable in the grooves so that the sides of the groove and those of the block as well are subject to wear.

Further, a coupling has been designed comprising a pliable and substantially non-resilient element having its ends secured to the driving shaft and the opposed shaft and coiled about the end portions of said shafts, said element being wound up tightly so as to transmit rotary motion from the driving shaft to the opposed shaft at such times as the said shafts are rotated continuously, but to be merely alternately uncoiled and wound up without transmitting the drive at such times as the driving shaft is reciprocated.

The disadvantages referred to are avoided in accordance with the present invention by assembling the coupling of the plurality of coupling discs mounted for free rotation on the counter-shaft and provided each with an arcuate groove and a coupling stud which is adapted to engage in the arcuate groove of the adjacent disc, the arcuate grooves of the discs being concentric with the counter-shaft and being interrupted in a portion of their length so that they do not form a complete circle.

Further advantages and features of the invention will appear from the following detailed description when read in conjunction with the accompanying drawings in which

Figure 1 is a perspective view of the elements of a coupling in accordance with the present invention;

Figure 2 is a sectional view showing a built-in coupling in conjunction with the discharge drum for the ready product and a hand operated device for disengaging the coupling;

Figure 3 is a section along the line I—I of Figure 2; and

Figure 4 shows diagrammatically the arrangement of the counter-shaft relatively to the knitting cylinders and to the product discharge drum.

One end of the counter-shaft 1 (Figures 1 and 2) is formed with a key slot 2 in which a key 4 may slide under the pressure of a spring 3 arranged in the axis of the shaft 1. The nose 5 of the slideable key 4 engages in a slot 6 provided in the boss of a disc 7 which is mounted for free rotation on the counter-shaft 1. The end of an eccentrically arranged stud 8 projects from the disc 7 and engages in an arcuate groove 9 (Figure 1) provided in an intermediate disc 10 which also is mounted for free rotation on the counter-shaft 1. The end of another eccentrically arranged stud 11 projects from the disc 10 and engages in an arcuate groove 12 formed in a disc 13. The latter is also mounted for free rotation on the counter-shaft 1 and the end of an eccentrically arranged stud 14 projects from the disc 13 and engages in an arcuate groove 15 formed in a combined disc and gear wheel 16 which is mounted for free rotation on the counter-shaft 1. All the arcuate grooves are interrupted in a portion of their length, as illustrated in Figure 1. The unit formed by the discs transmits the motion of the gear wheel 16 to a gear wheel 17 which has the double of the number of teeth of the gear wheel 16 and is fastened by means of screws to the product discharge drum 18 so as to rotate the latter together with the knitted product (Figure 4).

The device so far described operates as follows:

During the period of circular knitting the shaft 1, which is driven by the main shaft 20 over a bevel gearing 21, 22 and a spur gear transmission 23, 24, rotates permanently in one direction and through the gear wheel transmission 25, 26 imparts synchronous rotary motion to the upper and lower cylinders 27 and 28 in clockwise direction. The key 4 is urged in axial direction by the spring 3 in such a way that its nose 5 engages in the slot 6 provided in the boss of the disc 7. The connection thus established causes the disc 1 to be driven, and through the intermediary of the studs 8, 11 and 14 which bear against the ends 9a, 12a and 15a, respectively, of the corresponding arcuate grooves 9, 12 and 15, the discs 10 and 13 and the combined disc and gear wheel 16 are also rotated in the same direction.

During the period of knitting the heel pockets, when the knitting cylinders 27 and 28 and the counter-shaft 1 perform an oscillatory movement, the coupling shall not transmit this movement to the gear wheels 16 and 17 and to the discharge drum 18. Upon reversal of the direction of rotation of the shaft 1 (in counter-clockwise direction), the disc 7 rotates with the shaft 1, being coupled with the latter by the nose 5 of the key 4 and the slot 6. The stud 8 of the disc 7 leaves the end 9a of the groove 9 in the disc 10 and moves along this groove to its other end 9b, until contact is established between the stud and the groove end 9b. In this moment the disc 10 is caused to rotate and its stud 11 which moves freely along the groove 12 of the disc 13 will reach the other end 12b of the groove and rest against this last mentioned end. Thereby also the disc 13 will be caused to rotate; the stud 14 of the disc 13 will move freely along the groove 15 in the gear wheel 16 towards the other end 15b of the groove, but without reaching this end. However, the gear wheel 16 cannot rotate, its rotation being prevented by its cooperating gear wheel 17 which is loaded by the weight of the

drum 18 and of the knitted product in the latter. The sum of the arcuate lengths of all the arcuate grooves 9, 12 and 15 is greater than the circumferential path of the knitting cylinders for a complete rotation. Upon the next reversal of the rotation of the shaft 1 to clockwise direction the just described process is repeated in the reverse sequence. Therefore, during the period of knitting the heels and toes of stockings, this operation takes place at each reversal of the movement to clockwise and counter-clockwise direction.

A hand operated disengaging device is provided to permit a temporary release of the rigid connection between the counter-shaft 1 and the discharge drum 18, or a disengagement of the noiseless coupling in accordance with the invention when required, e. g. in the case of damage of the machine, repair, exchange of parts etc.

The counter-shaft 1 has provided at its end portion an axial cylindrical bore to receive a screwed-in member 29 which again is provided with a bore through which passes a screw 30 adapted to be screwed into the key 4, as shown in Figures 2 and 3. The nose 5 of the key 4 is forced by the spring 3 into the slot 6 of the disc 7 whereby also the screw 30 is pulled inwards, the head of the latter pressing against a washer 31 in which pins 32 are secured by a pressing operation or otherwise, the pins 32 engaging in blind holes 33 provided in the member 29. The connection thus established between the counter-shaft 1 and the noiseless coupling in accordance with the present invention may be released by exerting an outward pull on the washer 31 by hand and turning it in such a way that the pins 32 of the same are disengaged from the holes 33 in the member 29. The axial displacement thus taking place causes the screw 30, and the key 4 rigidly connected to the latter, to be pulled out. Thereby the nose 5 of the key 4 is withdrawn from the slot 6 in the boss of the disc 7, so that then the counter-shaft 1 rotates alone since the discs 7, 10 and 13 and the gear wheel 16, as well, are mounted for free rotation on the counter-shaft. The described device preferably is housed in a casing 34 which serves at the same time as a bearing for the gear wheel 17.

What I claim is:

In a double cylinder circular knitting machine 50 including in combination driving means adapted to drive the knitting cylinders continuously in one direction during normal rotary knitting and in alternate rotary directions of limited extent during other periods, a countershaft geared to 55 rotate in unison with said knitting cylinders in all directions of rotary motion thereof, fabric draw-off mechanism for said knitting cylinders and a driving coupling between said countershaft and said draw-off mechanism, the improved construction wherein said driving coupling between said countershaft and said draw-off mechanism 60 comprises a series of adjacent coupling discs each of which excepting the first is freely rotatable on said countershaft, each of said discs excepting the last of the series having an eccentrically positioned pin projecting from one face thereof and each of said discs excepting the first of the series having an arcuate groove in its opposite face concentric with the axis thereof, each of said grooves seating the pin of the disc adjacent thereto, means for keying the first disc of the series to said countershaft and means for driving the draw-off mechanism from the last disc of the series, the sum of the circumferential 65 lengths of the arcuate grooves in said coupling

discs being greater than the angle of rotary motion of said knitting cylinders as imparted to said counter-shaft during the periods of alternate rotary motion of said knitting cylinders, whereby to drive said draw-off mechanism continuously in unison with said knitting cylinders during normal rotary knitting periods and to completely interrupt the drive thereto during the periods of alternate rotary motion of said knitting cylinders.

BOHUMIL CHARVÁT.
